UNITED STATES PATENT OFFICE.

JOHN LA BURT, OF BROOKLYN, NEW YORK, ASSIGNOR OF TWO-THIRDS TO
ALBERT E. SPENCER AND HENRY A. KESSEL, OF SAME PLACE.

DISPLAY-HOOK.

SPECIFICATION forming part of Letters Patent No. 679,900, dated August 6, 1901.

Application filed February 26, 1901. Serial No. 48,920. (No model.)

To all whom it may concern:

Be it known that I, JOHN LA BURT, of the
borough of Brooklyn, county of Kings, State
of New York, have invented a new and useful
5 Improvement in Display-Hooks, of which the
following is a specification.

My invention relates to improvements in
hooks to serve as supports for manufactured
articles as displayed in shop-windows; and it
10 consists in the features of construction here-
inafter described and claimed.

The accompanying drawing, forming part
of this specification, is a perspective view of
my invention, which consists of a wire hook
15 adapted to be suspended upon a suitable sup-
port and having at its other end a clamp for
engaging the article to be exhibited and an
intermediate holder for a price-card.

As shown, the device is made up of two
20 parts, the hook A, for engaging a support, and
the clamp member B, suspended upon the
hook and retained thereon by means of the
head 2. The clamp member is made up of a
single piece of spring-wire, formed at the top
25 with a spiral eye 3 and at its bottom with a
similar eye 4, through both of which the hook
A is passed. The side portions *a* and *b* of
the clamp member are substantially parallel
with each other and terminate, respectively,
30 in circular eyes 5 and 6, which serve as the

clamping-jaws. The part B has an intermediate
spiral 7, which serves as a price-card
holder.

In use the article to be exhibited is engaged
by the jaws 5 and 6 and the whole supported 35
by means of the hook A upon a rod or other
suitable device, while a price-carrying card
may be inserted in the spiral cell, the clamp
member turning freely upon the shank of the
hook A. 40

I claim—

A display-hook comprising in combination,
a hook member and a clamp member, the lat-
ter being formed of a single piece of wire bent
upon itself, the ends thereof serving as the 45
jaws of the clamp, which are held normally
closed by the resiliency of the wire, a spiral
formed in the wire on one side of the clamp
member adapted to receive a price-card, and
spiral eyes formed in the wire at the top and 50
bottom of the clamp member engaged by the
hook member and serving as a swivel connec-
tion therefor.

Signed at New York city this 20th day of
February, 1901.

JOHN LA BURT.
